VAPOR ELECTRIC DEVICE

Leon R. Ludwig, Forest Hills, Pa., assignor to
 Westinghouse Electric & Manufacturing Company, East Pittsburgh, Pa., a corporation of Pennsylvania

Application November 11, 1933, Serial No. 697,689

3 Claims. (Cl. 250—27.5)

My invention relates to a vapor electric device and particularly to a cathode construction for a make-alive type converter.

The engineers employed in constructing and 5 designing vapor electric converters have long realized that certain advantages could be obtained by operating a simple rectifier having the anode directly exposed to the cathode and closely spaced with regard thereto. However, until the 10 invention of the make-alive type of exciter there were many practical reasons preventing the satisfactory operation of such a simple converter. In the operation of simple converters of the make-alive type, it has been found that excess 15 vapor pressure in the converter sometimes leads to unsatisfactory operation.

It is an object of my invention to provide a 20 cathode construction for such a converter that will greatly reduce the danger of failure of valve action.

It is a further object of my invention to provide a converter construction having a reduced 25 arc drop and low energy loss.

In the converter, according to my invention, 30 the cathode is provided with a spot fixing body partially immersed in the cathode material and the make-alive electrode is so positioned that the cathode spot is initiated directly on the spot fixing body, preferably at the junction of the spot fixing body with the cathode material. If 35 this cathode and spot fixing body are suitably cooled, the resulting vapor pressure in the converter will be greatly reduced.

In practice it has been found that when an 40 arc plays directly to a mercury surface there is a blast of high velocity vapor produced whether by electrical or mechanical action as yet unknown. However, by fixing the cathode spot on a spot fixing body this direct vapor blast is substantially avoided. Tests have indicated that 45 this direct blast impinging on the exposed anode greatly reduces the reliability of the valve action of the converter.

It is accordingly an object of my invention 50 to prevent a direct vapor blast in the converter.

Tests with a converter provided with the cathode according to my invention disclosed an unexpectedly low arc drop, said arc drop being 55 of the order of six to eight volts with a consequent reduction of energy loss in the device.

Other objects and advantages of my invention will be apparent from the following detailed description taken in conjunction with the 60 accompanying drawing, in which

Figure 1 is a sectional elevation of a converter embodying my invention, and

Fig. 2 is a sectional view of the cathode of my improved converter taken along line II—II of Fig. 1.

The apparatus, according to my invention comprises a simple rectifier having a cathode 1 of mercury or other suitable vaporizable material and an anode 2 directly exposed to the cathode 1 and separated therefrom by a suitable insulator 3. A suitable make-alive electrode 5 having a tip of resistance material which extends into the converter and makes contact preferably by immersing a portion of the tip of the make-alive electrode 5 in the material of the cathode 1.

A suitable spot fixing body such as the molybdenum covered coil 6 is partially immersed in the cathode material. This spot fixing coil 6 is so positioned that a portion of the coil is in contact with the make-alive electrode 5 in such manner that the make-alive electrode 5, the spot fixing body 6 and the surface of the cathode material 1 meet at a common point.

In order to insure that the cathode spot will be struck on the spot fixing body 6 preferably at the junction of the spot fixing body 6 with the surface of the cathode 1, I provide an insulating coating 8 such as glass on the major portion of the make-alive electrode 5, however, providing a small opening 9 in the insulating 30 covering 8 permitting contact between the spot fixing body 6 and the electrode 5 at the surface of the cathode material 1.

In the operation of my converter, the application of ignition potential to the make-alive electrode 5 produces a cathode spot directly on the spot fixing body 6 at the junction of the spot fixing body 6 with the cathode material 1. When the main arc strikes to this cathode spot, it will spread directly along the spot fixing body 6 and will not wander over the surface of the cathode material.

In order to further reduce the material evaporated from the cathode, the cathode 1 is thoroughly cooled, preferably by circulating a 45 cooling fluid through the spot fixing body 6. In any event, it is desirable that both the cathode material and the spot fixing body 6 be thoroughly cooled when my converter is in operation.

While I have shown and described a specific embodiment of my invention, it will be apparent to those skilled in the art that many changes and modifications can be made therein without departing from the true spirit of my 55

invention or the scope of the accompanying claims.

I claim as my invention:

- 5 1. A vapor-electric device comprising an evacuated container, a pool type cathode therein, a main anode cooperating with said cathode, a make-alive electrode having a tip of resistance material dipping into said pool type cathode during normal operation of the device, a spot fixing body partially immersed in said cathode, said make-alive electrode and said spot fixing body having a point of common contact with each other and the surface of the cathode and an insulating covering on the remainder of the 10 surface of the tip of the make-alive electrode.
- 15 2. A vapor-electric device comprising an evacuated container, a pool type cathode therein, a main anode cooperating with said cathode, a make-alive electrode having a tip of resistance material dipping into said pool type cathode during normal operation of the device, a spot fixing body partially immersed in said cathode, 10 said make-alive electrode and said spot fixing body having a point of common contact with each other and the surface of the cathode and a vitreous covering on the remainder of the 15 surface of the tip of the make-alive electrode.
- 20 20

molybdenum covered coil through which cooling fluid is passed partially immersed in said cathode, said make-alive electrode and said molybdenum covered coil having a point of common contact with each other and the surface of the cathode and an insulating covering on the remainder of the surface of the tip of the make-alive electrode.

3. A vapor-electric device comprising an evacuated container, a pool type cathode therein, a main anode cooperating with said cathode, a make-alive electrode having a tip of resistance material dipping into said pool type cathode during normal operation of the device, a spot fixing body partially immersed in said cathode, 10 said make-alive electrode and said spot fixing body having a point of common contact with each other and the surface of the cathode and a vitreous covering on the remainder of the 15 surface of the tip of the make-alive electrode.
